DESIGN FOR A BROOCH OR SIMILAR ARTICLE

Adolph Katz, Providence, R. I., assignor to Coro, Inc., New York, N. Y., a corporation of New York

Application May 31, 1946, Serial No. 130,257

Term of patent 7 years

(Cl. D45—19)

To all whom it may concern:

Be it known that I, Adolph Katz, a citizen of the United States of America, residing in Providence, county of Providence, and State of Rhode Island, have invented a new, original, and ornamental Design for a Brooch or Similar Article, of which the following is a specification, reference being had to the accompanying drawing, forming part thereof.

Fig. 1 is a plan view of a brooch or similar article showing my new design.

Fig. 2 is an edge view thereof.

The characteristic feature of my design for a brooch or similar article comprised of outlined petals, resides in the specific arrangement of the differently sized and shaped gems within each petal, the arrangement of the gems being varied in each petal, as shown.

I claim:

The ornamental design for a brooch or similar article, substantially as shown and described.

ADOLPH KATZ.
